UNITED STATES PATENT OFFICE

JOHN MARK LIGHT, OF ANNVILLE, PENNSYLVANIA

AEROPLANE BRAKE

Application filed August 13, 1929. Serial No. 385,675.

The present invention relates to a brake for heavier than air craft and has for its prime object to provide an apparatus of this nature which may be used to advantage on 5 aeroplanes and other heavier than air craft so as to break the speed of the aircraft when nosing downwardly in making a landing or the like as becomes necessary at times to prevent crashes, accidents and the like.

Another very important object of the invention resides in the provision of a braking action of this nature which is simple in its construction, strong and durable, compact and convenient in its arrangement of parts, 15 easy to manipulate, thoroughly efficient and reliable in use and operation, and otherwise well adapted to the purpose for which it is designed.

With the above and numerous other objects 20 in view as will appear as the description proceeds, the invention resides in certain novel features of construction, and in the combination and arrangement of parts as will be hereinafter more fully described and claimed.

In the drawings:

Figure 1 is a side elevation of a monoplane showing my apparatus incorporated therein,

Figure 2 is a front elevation thereof,

Figure 3 is a longitudinal section through 25 the apparatus,

Figure 4 is a sectional elevation of the apparatus showing the parts in closed position,

Figure 5 is a transverse section taken substantially on the line 5—5 of Figure 3,

Figure 6 is a transverse section taken substantially on the line 6—6 of Figure 3,

Figure 7 is a transverse section taken substantially on the line 7—7 of Figure 3,

Figure 8 is a transverse section taken substantially on the line 8—8 of Figure 3.

Referring to the drawing in detail it will be seen that the numeral 5 denotes an elongated cylindrical tube the forward end of which is flared outwardly and has secured at its forward end a funnel 6. This funnel 6 comprises a plurality of sections or plates 6' each of which are substantially V-shaped in formation in cross section and have their smaller ends secured to the flared outer edge of the

tube 5 through the medium of spring hinges b.

The plates 6' of the funnel have their adjacent edges disposed in overlapping relation, and each of said plates adjacent its outer or free edge and extending inwardly from one side edge thereof is provided with a slot a, while on the opposite side edge adjacent its free end each of the said plate sections b' is provided with a pin c adapted for sliding movement in the slot of the next adjacent funnel plate 6'.

The spring hinges b will manifestly normally urge the plate section 6' of the funnel outwardly to that position illustrated in Figure 3.

A spider like frame 9 is mounted in the front or larger end of the casing 7 and has a bearing 10 at the center thereof. A gear housing 11 is mounted in the central portion of the tube 5 being fixed therein by means of a base 12 and the rear end of the casing 7 fits over the front portion of the housing 11.

A shaft 14 is journaled through the front portion of the housing 11 and through the bearing 10 and terminates forwardly of the funnel 6 in a head or stop 15. A plurality of propellers 16 are mounted on the shaft 14 in spaced relation to each other between the frame 9 and the housing 11 so that a current of air through the casing 7 caused by the forward movement of the apparatus will turn the shaft 14 in the direction of arrow 18 that is in a clockwise direction when referring to Figure 7.

A cone shaped nose and closure 19 has a bearing 20 at its apex slideable on the forward portion of the shaft 14 and this bearing is provided at its rear end with an annular shoulder 21. A spring 22 is disposed about the forward portion of the shaft 14 and impinges against the bearing 10 and the bearing 20 to normally hold the nose closure 19 in an open position as shown in Figure 3.

A bracket arm 24 extends from the spider frame 9 and has a catch 25 pivotally engaged thereon for engaging the shoulder 21 and holding the nose closure in a closed position as shown in Figure 4 with the spring 22 under tension so that by pulling a cable 26 the catch 25 may be swung to free itself from the

shoulder 21 and the spring 22 will urge the nose closure 19 forwardly from the closed position shown in Figure 4 to the open position shown in Figure 3.

5 Within the housing 11 on the rear end of the shaft 14 there is fixed an internal gear 27 with which meshes a pinion 28 on a shaft 29 journaled in bearing 30 projecting forwardly from the rear side of the housing 11. A bearing 31 is formed in the center of the rear of the housing 11 and has journaled therein a shaft 32 extending rearwardly and journaled in a bearing 33 formed at the center of spider frame 34 in the rear end of the tube 5.

15 A plurality of propellers 36 are mounted on the shaft 32 within a rearwardly tapering frusto-conical casing 37 the front end of which is disposed over the rear portion of the housing 11 and notched as at 39 while the 20 rear end meets the spider frame 34 and is notched as at 40.

The shaft 32 extends rearwardly beyond the spider frame 34 and has a spiral thread or groove 41 formed thereon. A tail 42 comprises a concavo-convex front plate 43 and a concavo-convex rear plate 44. These plates are reduced in opposite directions and jointed together at their periphery.

25 The center of the plate 43 is threaded on the threaded end 41 of the shaft 32. The cable 26 is guided through a guide opening 47 in the case 12.

In Figures 1 and 2 I have illustrated one 30 practical installation or application of the apparatus. Two apparatuses shown, one under each side of the single plane and controlled by cables 26 leading to a lever 50 in the cockpit of the fuselage 51 under the center of the wings 52.

35 One apparatus, of course, is at each side of the fuselage, the nose closure 19 is forced back to the position shown in Figure 4 and has receivable in its widest end the plate 6' of the funnel 6 for maintaining the plate inwardly against the action of their respective spring hinges thus closing the entire front 45 end of the tube 5, and the tail 42 is returned so as to take the position shown in Figure 4 that is, inwardly against the spider 34 for closing the tube at this end of the tube.

50 Whenever it is desired to suddenly break the downward nose dive or the like of the airplane the lever 50 is actuated to pull the cables 26 and release the catches 25 so that the closures 19 move forwardly by the expansions of the springs 22, and the section plates 6' of the funnel are urged outwardly to an opened position as shown in Figure 3. The action of their respective spring hinges 6 so that air enters the funnel 6 and starts rotating the propellers 16 and the shaft 14 and the air passes rearwardly through the opening 8 between the tube 5 and the casing 37 and through the spider 34.

55 Simultaneously, of course, the shaft 32 is

rotated in the direction opposite to the shaft 14 through gearing 28 and 28', the latter gear being on the front end of the shaft 32 and in mesh with the gear 28 but the propellers 36 tend to suck the air from the rear notches 40 and force it out through notches 39.

60 The rotation of this shaft 32 will cause the tail 42 to move rearwardly because of the threaded end 41. Thus it will be seen that a great and effective braking action is occasioned by the current of air set up in an automatic manner which will tend to retard the aeroplane quickly and efficiently besides being especially reliable under aviation conditions.

65 It is thought that the construction, operation, utility and advantages of this invention will now be quite apparent to those skilled in this art without a more detailed description thereof.

The present embodiment of the invention has been disclosed in detail merely for the purposes of exemplification since in actual practice it attains the features of advantage enumerated as desirable in the statement of the invention and the above description.

70 It will be apparent that changes in the details of construction, and in the combination and arrangement of parts may be resorted to without departing from the spirit or scope of the invention as hereinafter claimed or sacrificing any of its advantages.

75 Having thus described by invention, what I claim as new is:

1. An apparatus of the class described comprising a stationary tube, a shaft journaled in the forward end of the tube and having a plurality of propellers thereon, a second shaft journaled in the rear portion of the tube and having a plurality of propeller shafts thereon, means operatively connecting the shafts so that they will rotate in opposite directions under the influence of air pressure.

80 2. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft.

85 3. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing,

the rear end of the casing extending over the front of the housing and having notches.

4. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing, the rear end of the casing extending over the front of the housing and having notches, a rearwardly tapering casing extending from the rear of the housing to the rear of the tube and having notches in its front and rear end and being circumjacent the propellers on the second shaft.

5. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing, the rear end of the casing extending over the front of the housing and having notches, a rearwardly tapering casing extending from the rear of the housing to the rear of the tube and having notches in its front and rear end and being circumjacent the propellers on the second shaft, spider frames at the front and rear of the tube in which the shafts are journaled.

6. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing, the rear end of the casing extending over the front of the housing and having notches, a rearwardly tapering casing extending from the rear of the housing to the rear of the tube and having notches in its front and rear end and being circumjacent the propellers on the second shaft, spider frames at the front and rear of the tube in which the shafts are journaled, a conical closure for the front end of the tube, said closure being formed with a bearing at its apex slideable on the first shaft which extends forwardly beyond the front spider, a spring on the first shaft tending to hold the closure normally in an open forward position, releasable means for holding the closure in a

normally in an open forward position, releasable means for holding the closure in a rearward closed position.

7. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing, the rear end of the casing extending over the front of the housing and having notches, a rearwardly tapering casing extending from the rear of the housing to the rear of the tube and having notches in its front and rear end and being circumjacent the propellers on the second shaft, spider frames at the front and rear of the tube in which the shafts are journaled, a conical closure for the front end of the tube, said closure being formed with a bearing at its apex slideable on the first shaft which extends forwardly beyond the front spider, a spring on the first shaft tending to hold the closure normally in an open forward position, releasable means for holding the closure in a rearward closed position, the second shaft extending rearwardly of the rear spider and threaded, a tail closure threadedly mounted on the second shaft and normally disposed against the rear spider to close the rear end of the tube, but being moved rearwardly to an open position by the rotation of the second shaft.

8. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing, the rear end of the casing extending over the front of the housing and having notches, a rearwardly tapering casing extending from the rear of the housing to the rear of the tube and having notches in its front and rear end and being circumjacent the propellers on the second shaft, spider frames at the front and rear of the tube in which the shafts are journaled, a conical closure for the front end of the tube, said closure being formed with a bearing at its apex slideable on the first shaft which extends forwardly beyond the front spider, a spring on the first shaft tending to hold the closure normally in an open forward position, releasable means for holding the closure in a

rearward closed position, the second shaft extending rearwardly of the rear spider and threaded, a tail closure threadedly mounted on the second shaft and normally disposed against the rear spider to close the rear end of the tube, but being moved rearwardly to an open position by the rotation of the second shaft, the front end of the tube merging into a forwardly flaring funnel.

9. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing, the rear end of the casing extending over the front of the housing and having notches, a rearwardly tapering casing extending from the rear of the housing to the rear of the tube and having notches in its front and rear end and being circumjacent the propellers on the second shaft, spider frames at the front and rear of the tube in which the shafts are journaled, a conical closure for the front end of the tube, said closure being formed with a bearing at its apex slidable on the first shaft which extends forwardly beyond the front spider, a spring on the first shaft tending to hold the closure normally in an open forward position, releasable means for holding the closure in a rearward closed position, a funnel secured to the front end of said first mentioned casing, said funnel comprising a plurality of sections, spring hinges securing the respective sections to said end of the said first mentioned casing, a pin and slot connection between the sections of the funnel adjacent the free end of the funnel, the sections of the funnel having their adjacent edges disposed in overlapping relation, and said sections adapted to be normally received in the widest end of said closure when said closure is in a rearwardly disposed closed position.
10. An apparatus of the class described comprising a tube, a shaft journaled in the forward end of the tube and having a plurality of propellers thereon, a second shaft journaled in the rear portion of the tube and having a plurality of propeller shafts thereon, gearing operatively connecting the shafts so that they will rotate in opposite directions, a rearwardly tapering casing in the forward end of the tube circumjacent the propellers on the first shaft, a housing for said gearing, the rear end of the casing extending over the front of the housing and having notches, a rearwardly tapering casing extending from the rear of the housing to the rear of the tube and having notches in its front and rear end

and being circumjacent the propellers on the second shaft, spider frames at the front and rear of the tube in which the shafts are journaled a conical closure for the front end of the tube, said closure being formed with a bearing at its apex slidable on the first shaft which extends forwardly beyond the front spider, a spring on the first shaft tending to hold the closure normally in an open forward position, releasable means for holding the closure in a rearward closed position, the second shaft extending rearwardly of the rear spider and threaded, a tail closure threadedly mounted on the second shaft and normally disposed against the rear spider to close the rear end of the tube, but being moved rearwardly to an open position by the rotation of the second shaft, the front end of the tube merging into a forwardly flaring funnel, said funnel comprising a plurality of sections, means for hingedly connecting the sections of the funnel to the front end of said tube, the sections of the funnel being disposed in overlapping relation, a pin and slot connection between the sections and their overlapping edges, said sections adapted to be received in the widest end of said closure, and spring means for normally urging the sections outwardly to an open and extended position when said closure is moved forwardly to an open position as and for the purpose specified.

11. An apparatus of the class described comprising a stationary tube, a shaft journaled in the forward end of the tube and having a plurality of propellers thereon, a second shaft journaled in the rear portion of the tube and having a plurality of propellers thereon, means operatively connecting the shafts so that they will rotate in opposite directions under the influence of air pressure, and selectively controlled means for rendering the propellers inoperative.

12. An apparatus of the class described comprising a stationary tube, a shaft journaled in the forward end of the tube and having a plurality of propellers thereon, a second shaft journaled in the rear portion of the tube and having a plurality of propellers thereon, means operatively connecting the shafts so that they will rotate in opposite directions under the influence of air pressure, and selectively controlled means for rendering the propellers inoperative, said last mentioned means including closures for the opposite ends of the tubes.

In testimony whereof I affix my signature.
JOHN MARK LIGHT.
